DESIGN FOR A COMBINED VACUUM CLEANER SUPPORT AND HOSE CARRIER

Dewey M. Dow, Frederick H. Burmeister, and Carl A. Lindberg, Toledo, Ohio, assignors to Air-Way Electric Appliance Corporation, Toledo, Ohio, a corporation of Delaware.

Application August 6, 1940, Serial No. 94,264

Term of patent 3½ years

To all whom it may concern:

Be it known that we, Dewey M. Dow, Frederick H. Burmeister, and Carl A. Lindberg, citizens of the United States, residing at Toledo, in the county of Lucas and State of Ohio, have invented a new, original, and ornamental Design for a Combined Vacuum Cleaner Support and Hose Carrier, of which the following is a specification, reference being had to the accompanying drawing, forming part thereof.

Fig. 1 is a perspective view of a combined vacuum cleaner support and hose carrier showing our new design.

Fig. 2 is a plan view of the same, the broken lines extending upwardly through the opening in the lower portion of Fig 1 being omitted for convenience of illustration.

We claim:

The ornamental design for a combined vacuum cleaner support and hose carrier, as shown and described.
